DESIGN FOR A LINEMAN'S CLIMBER

Harry B. Wilson, Wilmette, Ill., assignor to Mathias Klein & Sons, Chicago, Ill., a corporation of Illinois

Application November 2, 1939, Serial No. 88,013

Term of patent 7 years

To all whom it may concern:

Be it known that I, Harry B. Wilson, a citizen of the United States and a resident of Wilmette, in the county of Cook and State of Illinois, have invented a new, original, and ornamental Design for a Lineman's Climber, of which the following is a specification, reference being had to the accompanying drawing, forming a part thereof.

Figure 1 is a perspective view of a lineman's
climber showing my design;

Figure 2 is a side elevational view thereof; and Figure 3 is a rear elevational view thereof.

I claim:

The ornamental design for a lineman's climber,
as shown.

HARRY B. WILSON.
